UNITED STATES PATENT OFFICE.

FLORA BARNETT, OF NEW YORK, N. Y.

DESIGN FOR A COVERING FOR TOILET-BOTTLES.

SPECIFICATION forming part of Design No. 17,003, dated November 30, 1886.

Application filed October 23, 1886. Serial No. 217,071. Term of patent 3½ years.

To all whom it may concern:

Be it known that I, FLORA BARNETT, a citizen of the United States, residing at New York city, in the county of New York and State of New York, have invented and produced a new and original Design for the Coverings of Toilet or Cologne Bottles; of which the following is a specification, reference being had to the accompanying photograph, forming a part thereof.

Heretofore toilet or perfumery bottles have frequently been provided with a covering of some suitable fabric having impressed, painted, or otherwise worked upon its surface various ornamental designs or patterns, to enhance the beauty of appearance of the article and to impart an aesthetic effect to the dressing-table or other piece of furniture upon which the same may find a resting-place. To toilet-bottles of this class or character my invention relates.

The leading features of the design consist, first, in a bottle having its body portion ornamented with overlapping portions in imitation of the petals or leaves of a flower, and, secondly, in a bottle having its mouth surrounded by a floral ornament in substantial representation of a poppy or rose.

In the photograph which accompanies this application is shown in elevation a toilet-bottle embodying the several features of my novel design.

As will be seen, the body of the bottle is completely covered by floral portions a a, which partially overlap one another, after the fashion of the petals of a rose, and are preferably crimped or corrugated in more exact imitation of the leaves of a flower.

The neck of the bottle is ornamented by a ribbon or band, b, tied in a knot or bow, c, and serves as a line of demarkation between the 40 embellishment on the body of the bottle and that at the mouth thereof, and thus assists in augmenting the general beautiful effect of the entire decoration.

The mouth of the bottle is beautified by surrounding ornamentation substantially representing a rose or poppy, d, the petals of which are likewise preferably crimped or embossed.

At the base of the bottle is arranged a mat; 45 but this may be omitted, if desired.

It will be seen that by my novel design a toilet-bottle is produced with floral ornamentation at its body and at its mouth, and that the general effect of the same is at once striking and beautiful.

What I claim, and desire to secure by Letters Patent, is—

1. The design for the covering of the body of a toilet-bottle herein shown and described, consisting of the overlapping petal-like portions a a. 50

2. The design for the covering of a toilet-bottle herein shown and described, consisting of the overlapping petal-like portions a a and the floral ornament d. 65

3. The design for the covering of a toilet-bottle herein shown and described, consisting of the overlapping petal-like portions a a, the floral ornament d, and the dividing-band b.

FLORA BARNETT.
